United States Patent Office

Des. 206,195
Patented Nov. 8, 1966

206,195

PHOTOGRAPHIC SLIDE MOUNT PRESS OR SIMILAR ARTICLE

Stanley C. Kaiser, Quarters 6401, Air Force Academy,
El Paso County, Colo.

Filed Oct. 11, 1965, Ser. No. 87,384

Term of patent 14 years

(Cl. D61—1)

Fig. 1

Fig. 2

Fig. 3

I claim:

The ornamental design for a photographic slide mount press or similar article, as shown.
